No Drawing. 19 Pages Specification

A liquid, phosphorus-free cleaning formulation comprising a nonionic surface active agent in combination with an alkali cleaning compound or in combination with an amino polycarboxylic acid salt as a sequestering agent. Alternatively, a high level (from about 40 weight percent to about 70 weight percent) of the nonionic surfactant in an aqueous alcohol diluent may be employed without the inclusion of detergency builder compounds, sequestering agents or hydrotropes.
